(57) **CLAIM**

The ornamental design for a display device or portion thereof with graphical user interface, as shown and described.

DESCRIPTION

This application claims the benefit of U.S. application Ser. No. 16/398,145, filed 29 Apr. 2019, U.S. application Ser. No. 16/398,148, filed Apr. 29, 2019, the disclosure of each of which is incorporated, in its entirety, by this reference.

The FIGURE is a front view of a display device or portion thereof with graphical user interface.

The broken lines illustrate portions of the display device or graphical user interface that form no part of the claimed design.
